UNITED STATES PATENT OFFICE.

LINWOOD A. WALTERS, OF ALEXANDRIA, VIRGINIA, ASSIGNOR OF ONE-HALF TO ST.
CLAIR D. SHELTON, OF ALEXANDRIA, VIRGINIA.

RAILWAY-TIE.

1,161,091.

Specification of Letters Patent. Patented Nov. 23, 1915.

Application filed March 11, 1915. Serial No. 13,613.

To all whom it may concern:

Be it known that I, LINWOOD A. WALTERS, a citizen of the United States, residing at Alexandria, in the county of Alexandria and State of Virginia, have invented new and useful Improvements in Railway-Ties, of which the following is a specification.

This invention relates to improvements in railway ties and more particularly to a composition tie and a rail fastening means therefor.

It is the object of this invention to provide a railway tie composed of reinforced concrete or cement of such structure as to be able to resist the strain of heavy traffic without disintegrating and also to protect the lower corners from crumbling or breaking off.

It is a further object of this invention to provide a rail fastening device that will secure the rails in place without the use of exposed nuts or bolts, prevent the spreading of the rails, form an additional support for the outer side of the rail and allow the rails to be placed and removed without the necessity of turning the rail from the perpendicular, and also transmit the outward angular strain upon the top of the rail at curves to cause the device to more firmly grip the bottom of the flange upon the inner side of the rail.

While the preferred forms of this invention are illustrated upon the accompanying sheets of drawing yet it is to be understood that minor detail changes may be made therein without departing from the scope of this invention.

Figure 1 is a top plan view of this improved tie showing the reinforcing members in dotted lines, and illustrating the left rail of the track in dotted lines with the right rail in full lines as engaged by this improved fastening device. Fig. 2 is a transverse sectional view through the tie taken at the end of the I beam reinforcing member. Fig. 3 is a longitudinal vertical sectional view taken through the center of the tie illustrating the reinforcing members in side elevation. Fig. 4 is a central longitudinal vertical sectional view taken through this fastening device, showing the position of the rail in dotted lines. Fig. 5 is a view in end elevation of this device looking from the outer side of the track. Fig. 6 is a top plan view of this fastening device with the

locking and rail reinforcing member removed. Fig. 7 is a perspective view of a spring shock absorbing member. Fig. 8 is a top plan view illustrating the application of this improved fastening device to a wooden tie with parts broken away, and illustrating the left rail of the track in dotted lines with the right rail in full lines as engaged by this improved fastening device. Fig. 9 is a perspective view of a modification of Fig. 7. Fig. 10 is an enlarged top plan view of the rail hook.

The composition tie 1 as contemplated in this invention is of the usual dimensions of ties in common use by railroads and is formed of concrete, cement, or any other plastic material that is the equivalent for this purpose.

The main reinforcing member is an I beam 2 arranged centrally in the tie preferably terminating in line with the outer edge of the rail fastening device on each side of the track, and each end is supported by an inclined plate 3 bolted to the lower flange of the I beam resting and secured to an angle iron 4 forming the lower transverse edge of the end of the tie. By this construction not only is the molding of the tie simplified, as the reinforcing member is properly positioned and held during the filling of the mold, but the lower edge of the tie is reinforced by the angle iron anchored to the reinforcement and insures a proper support of the tracks by the tie end.

Each end 5 of the I beam is arranged parallel and a slight distance below the top of the tie 1 for supporting and securing a rail fastening base plate 6 preferably of galvanized iron which is bolted in place before the tie is molded. The ends of the I beam are then inclined downwardly toward the center to meet a horizontal central portion 7 of about equal length to the inclined portions 8 and substantially centrally located within the tie. The inclined portions 8 on each side are united by the rods 9 preferably two in number bolted or otherwise secured to the inclined portions and arranged on each side of the longitudinal center, which are embedded below the upper surface of the tie.

The base plates 6 for the fastening devices are preferably secured to the I beam by bolts passing through both upper and lower flanges and surrounded by sleeves 10.

between the flanges. As the base plates 6 are preferably flush with, or extend slightly above, the upper surface of the tie and are secured in place before the tie is molded, 5 they are embedded therein and the flat end surfaces 5 of the I beam are completely covered so as to be protected from the atmosphere or moisture.

The I beam formed with a central horizontal portion embedded substantially in 10 the center of the tie with the upwardly inclined portions on each side thereof terminating in horizontal rail supporting portions with the inclined portions connected 15 by tie rods forms in effect an inverted truss through which the weight upon the rails during traffic thereon is evenly transmitted from the ends throughout the entire body of the tie.

20 The improved rail fastening device designed for use with this composition tie comprises two spaced-apart securing plates 11 with their adjacent longitudinal sides 12 undercut to form a guide-way and engaging 25 means for a rail engaging member 13 mounted to slide therein. The rail engaging member 13 is of substantially the same height as the securing plates 11 with its sides inclined to correspond with the undercut sides 12 of the securing plates so that 30 it can slide longitudinally therebetween but will be held against vertical movement. One end of the rail engaging member 13 is 35 provided with a hook 14 upon its upper surface constructed and adapted to engage and hold the flange on one side of the rail and is provided with a transverse extension 14^a on each side of the hook 14 having inclined inner sides and ends adapted to engage under cut sides of corresponding cutout portions 40 on each securing plate adjacent thereto. The upper side of the other end of the rail engaging member 13 is provided with an upstanding heel or abutment 15 adapted 45 to pass through and above the securing plates 11.

The farther sides of the securing plates 11 adjacent the tie end are provided with corresponding upstanding ears 16 each terminating in a perpendicular inner edge. A locking and rail reinforcing member 17 is 50 removably secured between the ears 16 by a bolt 18 passing through the member and ears and secured in place by a cotter pin or nut 19. The locking and reinforcing member 17 is provided with a flat base 20 adapted to rest upon the securing plates 11 and is shaped upon the rail side to follow 55 the contour of the rail flange and web forming a shoulder 21 and rail web engaging portion 22 extending upward to the underside of the rail head with the opposite and outer side 23 inclined or curved downwardly to the outer end of the base 20 to form a 60 body of metal between the rail web and the

lower outer end. The base 20 is of such length that when the rail is placed upon the securing plates 11 against the vertical edges of the ears 16 and the rail engaging member is drawn through its guides so that its hook 70 14 engages the rail flange on the inner side of the track, the locking member 17 may be placed in position and the outer end thereof will engage the abutment 15 upon the outer end of the rail engaging member 13 and by 75 inserting the bolt 18 through the ears and locking member all parts of the fastening device will be held in operative position.

To absorb the shock of vibration caused by traffic upon the rails each securing plate 80 11 is preferably provided with two circular counter-sinks 24 arranged on each side of the center of the position assumed by the rail when in place, which are adapted to receive a spring shock absorbing member, 85 illustrated as a split washer 25, or the corrugated washer 26.

The securing plates 11 may be fastened to the base plate 6 on the composite tie by the heads of the bolts securing the base plate 90 to the I beam engaging in counter sinks in the securing plates.

Fig. 8 illustrates the application of this fastening device to a wooden or other tie 1^a in which the base plate 6^a extends along 95 the entire length of the tie and is secured thereto in any desired manner.

It is readily seen that no spikes are used or exposed securing nuts employed for securing the device to the tie or in operatively securing the parts of the device together which might work loose from vibration and cause the rails to spread or work loose from the fastening. The rails may be placed in position or removed in a perpendicular line as the rail engaging member is movable transversely of the rail to clear its hook of the rail edges and the ears are perpendicular so that it is not necessary to turn the rail in order that its flanges may be engaged or released by the fastening device. As the locking and rail reinforcing member is always on the outer side of the track the outward strain upon the rail on curves which tends to tilt the rail outward is 115 transmitted from the rail web through the locking and reinforcing member to the abutment 15 upon the rail engaging member 13 and through the rail engaging member to the hook 14 on the inner side of the track. 120

What I claim is:—

1. In combination with a railway tie, a rail fastening device comprising a base plate secured upon the tie, a sliding member mounted upon the base plate adapted to engage one flange of the rail and a locking member adapted to engage the opposite side of the rail flange and hold the sliding member in engagement. 125
2. In combination with a railway tie, a 130

5 rail fastening device comprising a base plate secured upon the tie, a sliding rail flange engaging member mounted thereon adapted to engage a rail flange, a locking and rail reinforcing member upon the other side of the rail locking said rail engaging member in engagement and engaging the rail flange and web, whereby a strain upon the reinforcing member will be transmitted to the 10 rail engaging member.

15 3. In combination with a railway tie, a rail fastening device comprising longitudinal spaced apart securing plates fastened upon the tie, a rail engaging member slidably mounted therebetween having a rail engaging hook upon one end and an upstanding abutment upon the other, upstanding ears upon the farther outer edges of said plates and a locking and rail reinforcing member 20 detachably secured therebetween engaging the abutment and the rail flange and web.

25 4. In combination with a railway tie, a rail fastening device comprising a base plate secured thereon, longitudinal spaced apart securing plates thereon having their adjacent sides undercut, a rail engaging member having inclined sides corresponding to said undercuts slidably mounted therebetween and having a rail engaging hook upon one 30 end and an upstanding abutment upon the other, ears upon the outer sides of the plates at the end adjacent the abutment, a locking and reinforcing member on the side of the rail opposite the hook having a shoulder 35 adapted to engage the rail flange and rail web opposite the hook with a portion engaging the abutments to hold the hook in engagement with the rail flange, and means

for securing said locking and reinforcing member between the ears on the securing 40 plates.

45 5. In combination with a railway tie, a rail fastening device comprising longitudinal spaced apart securing plates fastened upon the tie, a rail engaging member slidably mounted therebetween having a rail engaging hook upon one end and an upstanding abutment upon the other, upstanding ears upon the farther outer edges of said plates and a locking and rail reinforcing 50 member detachably secured therebetween engaging the abutment and the rail flange and web, shock absorbing members upon the securing plates upon which the rail rests, and means for holding the shock absorbers 55 in place.

6. In combination with a railway tie, a rail fastening device comprising longitudinal spaced apart securing plates fastened upon the tie, a rail engaging member slidably mounted therebetween having a rail engaging hook upon one end and an upstanding abutment upon the other, upstanding ears upon the farther outer edges of said plates and a locking and rail reinforcing 60 member detachably secured therebetween engaging the abutments and the rail flange and web, the upper surfaces of the securing plates adapted to receive the rail provided 65 with depressions, and spring shock absorbers 70 located within said depressions.
